UNITED STATES PATENT OFFICE.

ROBERT M. SULLY, OF PETERSBURG, VIRGINIA.

SEAL-LOCK.

SPECIFICATION forming part of Letters Patent No. 363,775, dated May 24, 1887.

Application filed March 22, 1887. Serial No. 231,961. (Model.)

To all whom it may concern:

Be it known that I, ROBERT M. SULLY, a citizen of the United States, residing at Petersburg, in the county of Dinwiddie and State of Virginia, have invented new and useful Improvements in Seal-Locks, of which the following is a specification.

The object of my present invention is to provide an improved construction of seal-lock for the doors of railroad freight-cars, whereby the car-door can be readily and conveniently secured and the withdrawal of the bolt effectually prevented until after the mutilation and removal of a seal connected with said bolt.

15 The object of my invention I accomplish in the manner and by the means hereinafter described and claimed, reference being made to the accompanying drawings, illustrating my invention, in which—

20 Figure 1 represents in side elevation a portion of a freight-car with my improved seal-lock applied thereto. Fig. 2 is a perspective view of the lock unfastened. Fig. 3 is a central vertical section showing the bolt with seal attached and locked in position. Fig. 4 is a view of the seal.

25 Referring to the drawings, the letter A designates the door of a freight-car, and B a hasp attached thereto. On one side of the door-frame is secured a plate, C, carrying a staple, D, for engagement with the hasp B on the car-door. Above the staple D, and in line therewith, is a lug, E, having a vertical perforation, a, through which is passed a locking-bolt, F, which also passes through the staple and through a vertical perforation, b, in a lug, G, located beneath the staple.

30 The upper end of the locking-bolt F has an enlarged head, c, formed with a shoulder or shoulders, d, resting on the upper surface of the lug E when the bolt is lowered, and preventing it from falling entirely through the staple and adjacent lugs. This enlarged head c forms a pivotal bearing for a hinged fastening-cap, 40 H, which may be made to engage the lug E in any suitable or convenient manner for locking the bolt F in position after the seal has been attached, as hereinafter explained. In the form of construction shown I prefer to flange 45 the free end of the hinged fastening-cap H on three sides, thereby forming in its end a recess, e, to engage and cover the upper front edge

and a portion of the upper side edges of said lug in front of the lowered bolt. I also arrange in the hinged fastening-cap H a catch, f, to engage a mortise, g, in the upper face of the lug E, and this catch may have a beveled face, as shown, and be provided with a spring, h, to facilitate its entrance into and engagement in said mortise, though a spring is not necessary.

55 The lower end of the locking-bolt F is formed to present a hook, i, for engaging a perforation, k, in a seal, K, when the bolt F is lowered through the lug G; and after the seal has been attached and the bolt raised the upper edge of the seal K will enter slits m m, formed vertically in each side of the lower perforated lug. By now throwing the fastening-cap H into locking engagement with the upper lug, 60 E, the bolt F will be securely held in such manner that it cannot be withdrawn without first mutilating and disengaging the seal.

65 The seal K preferably consists of a piece of thin sheet metal capable of being broken or torn under the application of a moderate force, but at the same time sufficiently tough and durable to afford adequate support and protection for a paper or card-board tag secured thereto by the upper and lower folded-over 70 edges of the metal. The perforation k, for engaging the hook i, is made through both the paper and metal; and along the upper folded edge of the seal, in line with the perforation k, is formed a line of perforations, n, to facilitate the tearing of the seal when connected with the locked bolt. On the paper or tag portion of the seal will be inscribed the usual information as to the point of shipment, destination, character of freight, &c.

75 Instead of arranging a seal, K, in connection with the hooked end of a locking-bolt, as above described, I may pass an ordinary twisted locking-wire, p, through a horizontal perforation, t, in the upper lug, E, and through a coinciding perforation, v, in the bolt F, and confine the ends of said wire by a lead seal, L, adjacent to the lug. This method of sealing 80 will afford a convenient and reliable substitute for the seal K when for any reason the latter is undesirable or is not at hand.

85 The operation and advantages of this seal-lock will be readily understood. By raising the bolt F sufficiently the hasp B can be

brought over the staple D, and when so raised the upward movement of the bolt is limited, and its disengagement from the lug E prevented by a stop, M, located adjacent to the 5 upper end of the plate C, as shown. When the bolt F is lowered into place through the staple D and in front of the hasp B, it can be readily secured either by a wire, p, passed through the perforations *t v* and held by a lead seal, L, or a seal, K, can be engaged with the hook *i* and slotted lug G and the hinged cap H brought into locking engagement with the upper lug, E, to prevent the further descent of the bolt.

15 It will be seen that when a seal, K, is attached to the hook *i* and drawn up into the slits *m m* the bolt cannot be raised further to disengage it from the staple, because the upper edge of the seal bears against the upper ends 20 of the slits *m m* and prevents movement of the bolt in that direction. If the fastening-cap H has not yet been applied, the bolt F can still be lowered, however, to allow the seal K to be removed, if desired, and the car door opened 25 before finally adjusting the seal; but after the seal K has been placed on the hooked end of the bolt and engaged in the slits *m m*, if the cap H is brought down on the lug E and engaged therewith, the bolt F can neither be 30 raised nor lowered, and the cap H being held securely by the catch *f* in the mortise *g*, the lock can be unfastened only after breaking and mutilating the seal. It is also apparent that when the parts are locked in the manner 35 described the hook *i* and upper edge of the seal K are both inclosed in the lug G, so that it will be impossible to remove the seal without mutilation.

It will be seen that in the construction and 40 operation this seal-lock is an improvement on the seal-locks for which Letters Patent No.

341,779 and No. 341,780 were granted to me May 11, 1886; and I would have it understood that I do not herein claim the construction set forth and claimed in said patents.

45

What I claim as my invention is—

1. In a seal-lock for cars, the combination of a perforated lug, a locking-bolt passed through said lug, and a fastening-cap hinged to the upper end of the bolt, and having a locking engagement with the lug when the bolt is in locking engagement with a connected seal, substantially as described.

50

2. In a seal-lock for cars, the combination of a perforated and mortised lug, a staple, a perforated and slotted lug, a locking-bolt passed through said lugs and staple and having a hook at one end, a seal adapted to engage said hook and slotted lug, and a fastening-cap hinged to the other end of the bolt and having a catch to engage the mortised lug, substantially as described.

55

3. In a seal-lock for cars, the combination of the lug E, having a perforation, *a*, and a mortise, *g*, the bolt F, and the fastening-cap H, hinged to the head of said bolt and provided with recess *e* and catch *f*, substantially as described.

60

4. In a seal-lock for cars, the combination of the staple D, the lug E, having perforation *a* and mortise *g*, the lug G, having perforation *b* and slits *m m*, the locking-bolt F, having hook *i* and shoulder *d*, and the fastening-cap H, hinged to the head of said bolt and provided with a catch, *f*, substantially as described.

70

In testimony whereof I affix my signature in presence of two witnesses.

R. M. SULLY.
